[57] CLAIM

The ornamental design for a rotatable game board, as shown and described.

DESCRIPTION

FIG. 1 is a top plan view of a rotatable game board showing my new design;

FIG. 2 is an elevational view looking from the side of FIG. 1, each side view being a mirror image of its opposite side view;

FIG. 3 is a bottom plan view thereof;

FIG. 4 is a partial, top plan view thereof with a tray removed to show the tray holders;

FIG. 5 is a partial, perspective view of the central chip holder in FIG. 4;

FIG. 6 is a partial elevational view of the exposed tray holder of FIG. 4;

FIG. 7 is a bottom plan view of a tray, the top plan view being shown in FIG. 1;

FIG. 8 is an elevational view showing the inner end of the tray of FIG. 7, the outer end being shown in FIG. 2;

FIG. 9 is a side elevational view of the tray of FIG. 7, the opposite side being a mirror image thereof; and

FIG. 10 is an elevational sectional view of FIG. 9.
